UNITED STATES PATENT OFFICE.

HARVEY SEGUR, OF CHICAGO, ILLINOIS, ASSIGNOR TO TITE-PACK FILLER CO., OF CHICAGO, ILLINOIS, A CORPORATION OF ILLINOIS.

CELL-CASE MACHINE.

Application filed August 24, 1922. Serial No. 584,087.

To all whom it may concern:

Be it known that I, HARVEY SEGUR, a citizen of the United States, residing at Chicago, in the county of Cook and State of Illinois, have invented a certain new and useful Improvement in Cell-Case Machines, of which the following is a full, clear, concise, and exact description, reference being had to the accompanying drawings, forming 10 a part of this specification.

My invention relates to cell-case machines and has to do more particularly with the type of machine arranged for making cell cases or fillers for egg crates, although, of course, not limited thereto. One of the 15 features of my invention is the provision of mechanism adapted for constructing the fillers with laterally extending flaps or flanges preferably on two of the outer strips, thereby providing a more effective 20 filler having various advantages.

In machines for making cell cases or fillers as heretofore used, so far as I am aware, longitudinal and transverse flat strips have been used and as a sufficient 25 clearance had to be provided so as to permit of ready insertion of the fillers in the boxes, the fillers did not pack tight in the boxes. This permitted of a shifting of the 30 entire filler in the box and resulted in a shifting or shaking of each entire layer of eggs in the box.

In order to make a flanged cell case which overcomes these disadvantages I have provided 35 certain improvements whereby the cell case is built up as heretofore with transverse and longitudinal strips, but as it is passed through the machine two of the outside strips are provided with a laterally extending flange preferably formed up as 40 part of and integral with the outside strips.

To this end I preferably pass the straw board to where the fillers are made through various steps, first preferably wetting it 45 along the line where the flange is creased or bent over and then bending the flange preferably before the transverse and longitudinal strips are assembled.

For a better understanding of my invention reference is to be had to the accompanying drawings in which—

Fig. 1 is a side elevation giving the general outline of a cell case machine having my invention applied thereto;

Fig. 2 is a top plan view of the machine

shown in Fig. 1 but with feed F and other parts removed;

Fig. 3 is a sectional view along the line 3—3 of Fig. 2 showing more in detail the mechanism for wetting the paper along the 60 bending line before the flaps are bent;

Fig. 4 is a sectional view along the line 4—4 of Fig. 2 of the wetting mechanism;

Fig. 5 is an enlarged transverse sectional view along the line 5—5 of Fig. 2, showing more in detail the feed rollers and particularly the new feed roll flange guide construction for the outside strips;

Fig. 6 is an enlarged transverse sectional view along the line 6 of Fig. 2 showing the 70 bending plate and presser block which starts the bending of the flange;

Fig. 7 is an enlarged transverse sectional view along the line 7 of Fig. 2 showing an advanced stage of the bending and 75 indicating how the flange is bent over against the strip;

Fig. 8 is a partial sectional view along the line 8 of Fig. 1 showing the improved shear construction for severing the flange 80 strips together with the driving mechanism therefor;

Fig. 9 is a side view of the cam and shear operating lever of Fig. 8 partly broken away to more clearly indicate the 85 construction thereof;

Fig. 10 is a bottom view of a portion of the driving cam of Fig. 8;

Fig. 11 is a section along the line 11 of Fig. 2 through a portion of the slitter rollers, showing more particularly the end construction which permits of a slitting of the card board with the flange bent upwardly;

Fig. 12 is an enlarged vertical section along the line 12 of Fig. 2 showing the 95 curved guide for the bent up flange where the paper passes under the punch; and

Fig. 13 is a perspective view showing the cell case or filler as it comes out of the machine.

Taking up the detail construction of the preferred form of my invention as illustrated herein, I have shown it in conjunction with a well known type of cell case machine of the character shown in the patent to Swift #622,403, dated April 4, 1899, a side view of which is shown in general outline in Fig. 1. The machine includes the usual frame having a main drive shaft 105 connected through a suitable clutch mech- 110

anism 16 and geared to the eccentric shaft 17. The eccentric shaft is connected by means of the crank 18 and drive rod 19 to the slitter roll mechanism operated by 5 the usual intermittent driving mechanism A. The side plate 20 of the slitter driving mechanism to which the rod 19 is attached, is also connected by means of the cam shaft drive rod 21 so as to reciprocate the plate 10 22 on the cam shaft 23 and intermittently advance the circular cam 24 to operate the shear mechanism B. Feed roll mechanism C is also provided, this being shown more in detail in Fig. 5 and arranged to feed the 15 longitudinal strips of the cell case forwardly to receive the transverse strips and to the shear where the complete section is cut off.

The usual feed roll mechanism F and 20 cut-off shears for the transverse strips is also employed although, of course, not shown in detail.

At the right end of Fig. 1 I have shown 25 the paper moistener at D, this being simultaneously controlled with the clutch lever 25 (at left of Fig. 1) so that when the clutch mechanism is thrown in to operate the machine the moistener is automatically rendered effective. And when the clutch is thrown out to disconnect the machine then 30 the moistener is automatically rendered ineffective.

In general the operation of the moistener and bending apparatus is as follows: The straw board is fed from the roll as usual 35 but before reaching the bending and cell case cutting mechanism it is passed through the moistener D where it is moistened on one side on a line where the flange is bent over thereby placing the paper in a state to be 40 folded without breaking the fibre. The paper is then fed on through the flange forming mechanism E and then onto the punch, slitting rollers, etc.

Now as to the moistener mechanism D and 45 which is shown more in detail in Figs. 1, 2, 3 and 4, this comprises a suitable pan 26 in which the moistening fluid is carried and which is preferably water. Rotating in the water pan is a pair of rollers 27 having a 50 peripheral rim 28 which will take up the water and apply it to the paper 29. This rim 28 is preferably made of leather and suitably fastened to the roller 27. The rolls are carried upon a shaft 30 so that they will 55 freely rotate by contact with the paper as it passes over the roller. A cover 31 is placed over the top of the water tank and has an opening through which the roller extends as indicated in Fig. 3. The cover 31 is pivotally supported at 34 so that it may be lifted up and thereby raise the paper 29 out of contact with the moistener roll. I preferably 60 operate the cover 31 by means of a crank 32 so that as the crank is reciprocated one way or the other the cover is

raised and lowered. The crank is preferably controlled by the clutch lever 25 of the main machine, and to this end is connected therewith by means of a rod 33. The connection is such that with the clutch lever 70 25 thrown into the position indicated in Fig. 1, that is with the clutch out, the moistener is rendered ineffective. When the clutch lever 25 is thrown to the left in Fig. 1, the main machine is thrown into operation and 75 the moistener cover 31 lowered so as to bring the paper 29 into contact with the moistener roll.

This automatic operation of the moistener is brought about to positively prevent the paper from soaking up the water when the machine is stopped. In order to keep the paper against the moistener rollers I position weighted rollers 35, one above each moistening roll, the shaft 35' for the weighted rollers being vertically slidable in the end brackets 37. I also apply weighting block 36 above the paper before it enters the moistener so as to flatten it.

Thus it will be seen that as the paper 29 is drawn through the moistener a narrow strip along its under side is moistened by the application of water thereto from the peripheral edge of the moistener roll. And it is along this moistened line that the sheet 95 is bent or turned up to form the flange.

Now as to the mechanism for bending or flanging the paper, I provide a guide along each edge the first portion of which is shown more in detail in Fig. 6 and consists of a 100 bent up edge 38 curved as indicated in Fig. 6 and against which the presser block 39 rests. The block 39 is formed so as to fit the curve of the plate 38 but with sufficient clearance to permit the paper 29 to pass therethrough. It will be noted from Fig. 6 that as the paper enters the forming devices 38-39 it is flat, but gradually curves up into an angular position as indicated at the right or sectional end of Fig. 6. The paper then passes on into the section of the former indicated in Fig. 7, passing under the curved member 40 where it is gradually bent over onto itself as indicated at the right or sectional end of Fig. 7. This final bending of the paper as indicated in Fig. 7, is so as to give a more permanent set to the flange in that it strains the paper so that when it finally passes through the machine into the finished filler it has a slight downward bend 110 so that it may be more readily pressed up flat against the sides and form a more compact package for shipping. It is to be understood that in shipping such cases the sides are squeezed together into a compact flat package with the flange 29' folded against the side of the filler.

The paper then passes on under the weighting or pressing roller 41 and then on through the gradually receding curved plate 130

42 where the flange is permitted to again resume an upright or right angular position before passing under the punch and through the slitter rollers. At the curved member 42

5 I also provide a component member 43 so that the paper is more positively guided into its upright position as it passes over the die 44.

10 The sheet of paper with its up-turned flanges 29' then continues on through the slitter roll mechanism G (Fig. 2) where it is cut into strips before being turned and passed into the feed roll mechanism C.

15 As to the slitter roll mechanism G, this is constructed so as to take the flanged sheet and cut it into strips and to this end I provide a clearance slot 46, as shown in Fig. 2, and more clearly in the enlarged section Fig. 11. Thus, the sheet 29 is drawn through the 20 slitter rolls without unbending the flanged sides 29'.

25 After the slitting of the sheet at G the cut strips are fed between the vertically disposed feed roller mechanism C, the various strips being turned over between the rolls as indicated by the curved lines in Fig. 2.

30 My present machine differs from those heretofore used however, in that the outer longitudinal strips have flanges formed thereon which are passed through the feed roll mechanism. In order to take care of the flanged strips I provide a new roller construction, making the outer rolls 47 of a sufficient diameter with a clearance underneath at 47' to take the flanged strip. I also provide a guide for the outer strips before they enter the feed roll mechanism so as to suitably guide the flanged strips into the rollers and preserve the flange. To this end 40 I use sheet metal members 48 gradually curved so as to receive the strip without distorting the same.

45 After the longitudinal strips 29 are punched, flanged and slitted they are advanced to receive the transverse strips from the transverse mechanism F in the usual manner and then the completed cell case is severed by the shearing mechanism shown more in detail in Figs. 8, 9 and 10.

50 In order to sever both the straight and flanged longitudinal strips without distorting or disfiguring the flanges, I provide a peculiar shearing device having both straight and angular shears. The straight shear blades are indicated at 49 in Fig. 8 and the angular shears at 50, the latter being such that the flanged strip is passed therethrough and then severed at the proper time without affecting the flange. The shear, 55 which is of the multiple type, has the movable blades connected to the cross bar 51 which is connected by a link 52 to the shear operating lever 53. This lever carries a roller 54 travelling in the groove 55 in the 60 cam 24 fixed to the cam shaft 23. The cam 65

slot is such, and the cam 24 is so rotated that the shears are operated each time a cell case is completed.

After the case is severed it is removed from the machine by the operator and folded up into a compact form with the flanges folded down against the side so that it may be readily packed into a more compact space and the flanges held against the sides. Then when the case is opened and put into the 70 crate the resiliency of the paper causes the flange to spring outwardly substantially to a right angle before it is placed down in the 75 crate.

What I claim as new and desire to secure by United States Letters Patent is:

1. In combination with a cell case machine arranged to cut and assemble longitudinal and transverse paper strips to construct the cell case, of mechanism for forming a flange on two of the outer strips thereof.

2. In combination with a cell case machine arranged to cut and assemble longitudinal and transverse paper strips to construct the cell case, of mechanism for forming a flange on two opposite ones of the outer strips thereof.

3. In combination with a cell case machine arranged to cut and assemble longitudinal and transverse paper strips to construct the cell case, of mechanism for forming a flange on two of the outer strips thereof and integral therewith.

4. In combination with a cell case machine arranged to cut and assemble longitudinal and transverse paper strips to construct the cell case, of mechanism for forming a flange on two opposite ones of the outer strips thereof integral therewith and extending laterally from a longitudinal edge thereof.

5. In combination with a cell case machine arranged to cut and assemble longitudinal and transverse paper strips to construct the cell case, of mechanism for forming a flange on two opposite ones of the outer strips thereof integral therewith and extending laterally from a longitudinal edge thereof, said mechanism including a device for moistening the paper along a line, and means for then folding it along the moistened line.

6. In combination with a cell case machine arranged to cut and assemble longitudinal and transverse paper strips to construct the cell case, of mechanism for forming a flange on two of the outer strips thereof, including moistening and flange forming devices operating upon a continuous roll of paper, means for rendering the cutting and assembling mechanism operative and inoperative, and means responsive to the operation of the latter said means to apply and remove the moistening means accordingly.

7. In combination with a cell case machine arranged to longitudinally slit a continuous roll of paper as it is fed to the machine, of a moistening device for wetting the paper near its outer edges as it is fed along, and a flange forming device at each edge of the paper for turning the portion of the paper between the moistened part and edge so as to form a continuous flange on the outer strips.
8. In combination with a cell case machine arranged to cut and assemble longitudinal and transverse paper strips to construct the cell case, of mechanism for forming a flange on two opposite ones of the outer strips thereof integral with and extending laterally from a longitudinal edge thereof, and a multiple shears for severing the flanged and other longitudinal strips for each completed cell case.
9. A multiple shears for use on a cell case machine which uses flanged strips in the case, said shears comprising straight and angular cutting blades, the latter substantially conforming in shape to the flanged strip to sever the same when so formed.
10. In combination with a cell case machine arranged to slit and assemble longitudinal strips from a continuous roll of paper for cell cases, of means for forming a flange on two of the outer strips thereof, said means including an apron having gradually turned up sides through which the paper is fed from the roll to gradually bend up the paper along the edges to form the flanges.
11. In combination with a cell case machine arranged to slit and assemble longitudinal strips from a continuous roll of paper for cell cases, of means for forming a flange on two of the outer strips thereof, before assembling, feed roller mechanism for feeding the strips after the slitting and flange forming, certain of the rollers having clearance construction so as to draw the flanged strips therethrough.
12. In combination with a cell case machine arranged to slit and assemble longitudinal strips from a continuous roll of paper for cell cases, of means for forming a flange on two of the outer strips thereof before slitting, and slitting mechanism comprising a pair of parallel slitter-rolls through which the paper is drawn after being flanged, said slitter rolls being constructed to receive the flanged sheet in its formed state.
13. The method of constructing flanged side cell cases which consists of taking two continuous sheets of suitable straw-board, slitting one sheet, transversely cutting the other, moistening the slit sheet longitudinally along bending lines near the outer edges thereof, bending the outer portions over to form flanges thereon, and assembling the longitudinal and transverse strips.
14. In combination with a cell case machine arranged to cut and assemble longitudinal and transverse paper strips to construct the cell case, of mechanism for flanging a strip thereof during the cutting and assembling, said mechanism including an apron having a gradually turned up side and component angular block to form a continuously gradually curving right angle slot through which the paper is fed to gradually bend up the paper to form the flange.
15. In combination with a cell case machine arranged to cut and assemble longitudinal and transverse paper strips to construct the cell case, of mechanism for flanging a strip thereof during the cutting and assembling, said mechanism including an apron having a gradually turned up side and component angular block to form a continuously gradually curving right angle slot through which the paper is fed to gradually bend up the paper to form the flange, and means for moistening the paper along a bending line at the point of the angle to facilitate the flanging thereof.
16. In combination with a cell case machine arranged to cut and assemble longitudinal and transverse paper strips to construct the cell case, of strip flanging mechanism therefor including moistening and flange forming devices operating upon a continuous roll of paper as it is fed to the machine, means for starting and stopping the cutting and assembling mechanism, and means for rendering the moistening device effective and non-effective with the starting and stopping of said mechanism.
17. In combination with a cell case machine arranged to cut and assemble paper strips from a continuous roll to construct the cell case, of strip flanging mechanism therefor including moistening and flange forming devices operating upon a continuous roll of paper, a manually controlled clutch device for starting and stopping the cutting and assembling mechanism, and means connecting said clutch operating device and said moistening device so as to apply the moistening device to the paper or remove it as the machine is started and stopped, respectively.
- In witness whereof, I hereunto subscribe my name this 7th day of August, A. D., 1922.

HARVEY SEGUR.
